UNITED STATES PATENT OFFICE.

WILLIAM J. GARRISON, OF SHEFFIELD, PENNSYLVANIA.

VAULT-LIGHT.

1,155,348.

Specification of Letters Patent.

Patented Oct. 5, 1915.

Application filed July 16, 1915. Serial No. 40,241.

To all whom it may concern:

Be it known that I, WILLIAM J. GARRISON, a citizen of the United States, residing at Sheffield, Warren county, Pennsylvania, have invented certain new and useful Improvements in Vault-Lights, of which the following is a specification.

This invention pertains to improvements in that class of vault-lights consisting of small individual glasses set in individual frames embedded in a concrete or cement slab.

My invention will be readily understood from the following description taken in connection with the accompanying drawing in which:

Figure 1 is a plan of my improved vault-light showing a group of the frames attached to each other, two of the frames being shown in conjunction with the embedding concrete or cement, and one of these latter frames being shown as being provided with its glass: Fig. 2 a diametrical section of one of the frames and its links, its glass appearing in elevation: Fig. 3 a side elevation of one of the links employed in attaching the frames to each other: and Fig. 4 a side elevation of an exemplifying tool which may be employed in removing a damaged glass from its frame.

In the drawing:—1, indicates a frame illustrated as being circular, as a mere example of form, of a size to freely receive the glass to be employed; 2, an upwardly presenting shoulder on the interior of the frame at such distance below the top rim of the frame as corresponds with the thickness of the glass; 3, the glass, the same being of a form and size less than that of the interior of the top of the frame and adapted to rest upon the shoulder 2 and fit the frame at its juncture with the shoulder; 4, a perimetrical groove in the glass; 5, a groove formed within the interior of the frame opposite the groove 4; 6, perforated ears, illustrated as being four in number, projecting outwardly from the frame intermediate between the base and the top rim of the frame; 7, wire links engaging the ears of the frame and adapted for connecting a group of frames together, these links being preferably in the form of staples having their ends engaging the perforations in the ears of the frames and then bent inwardly to prevent their displacement from the ears; 8, the cement or concrete in which the frames are embedded;

9, a tool well lending itself to employment when a glass is to be removed from its setting, this tool being in the form of a bar to serve as a handle; 10, a prong at one end of the tool to serve in removing the water-proof cement holding the glass in its setting; 11, a prong at the opposite end of the tool to serve in catching in the groove 4 of the glass; 12, a lug projecting from the tool at the side opposite prong 11 and at such distance from prong 11 that it may gage the depth of penetration of prong 11 into the space between the glass and the frame; and 13, water-tight cement, of usual composition, disposed in the space between the glass and that portion of the inside of the frame occupied by the glass.

One of the frames with its glass is to be viewed as an individual unit, and these units may be associated, at such distance from each other as may be desired, into a group embedded in the cement or concrete slab, the completed structure showing only the top of the glass and the top rim of the frame.

It is preferred that the general structures be formed in the shop, as a matter of convenience and economy, and later placed in the situation which they are to occupy. This slab, wherever made, will have a thickness equal to the depth of the frames which, it will be observed, is considerable more than the thickness of the glass.

In forming the general structure, the frames are to be disposed upon a suitable plane surface in such arrangement of pattern as is desired and coupled together by the links. These links may be of such length as corresponds with the desired distance apart of the frames. The links may be inserted into the ears of the frames and their ends bent after the frames are disposed upon the supporting surface or, if desired, the frames may be associated and linked together and then laid upon the supporting surface. The cement or concrete to form the slab is then to be placed around and between the frames and leveled off, as by troweling, level with the top of the frames. When the material of the slab has set, it may be removed from the supporting surface and transported and placed in its ultimate situation. The slab becomes a reinforced structure by reason of the embedded frames and their connecting links. If the slab is to be constructed in the situation which it is ultimately to occupy, then the

plane surface on which the slab is to be built may be formed by a suitably positioned and supporting platform.

If the links are employed merely for positioning agents in securing proper relationship between the frames, the strength of the links is immaterial so long as it will answer said purpose, but special reinforcing capacity will be derived from the links if they be of substantial size and material and are clenched tightly to the ears of the frames.

The glasses are to be placed in the frames concentric with the frames, the glasses centering themselves in the frames, and the water-proof cement applied around the glasses between them and the interior of the frames. The glasses may be applied to the frames before the frames are set upon the supporting surface in the process of forming the slab, or the setting of the glasses in the frames may be made the final element in the process of forming the slab. If a glass becomes broken and it be desired to replace it, then the water-proof cement around the defective glass is dug out by means of the tool 9, the prong 10 being used for this purpose. The opposite end of the tool is now inserted into the space between the glass and frame, lug 12 engaging the top of the frame and determining when the tool has been inserted into the space a proper distance to bring prong 11 into the neighbor-

hood of groove 4 in the glass. The tool is then used as a lever with lug 12 resting on the rim of the frame and the glass lifted or pried out of place.

I claim:

1. A vault-light comprising, a frame having an inward upwardly presenting shoulder and an interior recess above said shoulder, ears projecting from the exterior of the frame and adapted to receive links to connect the frame with similar frames, a glass adapted to rest upon said shoulder and have its upper surface flush with the rim of the frame and having a dimension less than that of the interior of the frame and having an exterior groove, and sealing material disposed within the frame around the glass and in the groove in the glass and in the recess in the frame, combined substantially as set forth.

2. A vault-light comprising, a group of frames provided with perforated exterior ears, a glass secured within each frame by sealing material, links engaging said ears and uniting the frames, and a slab of plastic material embedding said ears and links and surrounding the frames, combined substantially as set forth.

WILLIAM J. GARRISON.
